UNITED STATES PATENT OFFICE

2,049,131

AIR COMPRESSOR

Howard Morgan, Baltimore, Md.

Application December 17, 1934, Serial No. 757,841

12 Claims. (Cl. 230—217)

The invention refers to devices and systems for compressing air and gases, and has for its objects to raise the original pressure of the air or gas supply to a high point within the device in a compact and economical manner to provide for a system of cycles that may provide for the use of the air compressed to operate machines, and many other objects that will become apparent as the invention is more fully set forth.

10 The ordinary air compressor raises the pressure of air or gas directly in the first cylinder or compressor and then transmits it to a reservoir or service line. In this invention, the air or gas is raised in pressure by a series of travels through 15 the same cylinders, each time being raised in pressure and progressively advanced, and other apparatus is used in the system to convert the energy developed in a series of cycles peculiar to its own system and methods which are herein- 20 after to be described.

In this application no regard has been made to the effects of heat in the compression or expansion of air in the cylinders of the recompressors or other parts of the system, in order not to complicate the operation of other phases of the invention described.

In the drawings, which illustrate by way of example an embodiment of this invention:—

Figure 1 is a plan view of the apparatus involved in this invention.

Figure 2 is a sectional view in a longitudinal direction of one of the air recompressor cylinder units used in this apparatus.

Figure 3 is a sectional view along the line 3—3 of Figure 2.

Figure 4 is a sectional view along the line 4—4 of Figure 2.

Figure 5 is a longitudinal elevation of the motor unit used in the apparatus of this invention, along 40 the line 5—5 of Figure 1.

Figure 6 is a side view of the rack and pinion portion along the line 6—6 of Figure 1.

Figure 7 is an end elevation of the recompressor cylinder along line 11—11 of Figure 1.

45 Figure 8 is a diagrammatic view of the apparatus and method of operation.

Figure 9 is a sectional view of one of the air recompressor cylinder units, illustrating the application of the forces of air compression therein, in the manner and method peculiar to itself and herein further described.

Similar reference characters refer to similar parts throughout the drawings.

In the device and system there are several 55 distinct participating parts. These will be re-

ferred to as the compressor parts and the reservoir unit. The compressor units are made up of a series of four, in this embodiment, and marked 101, 102, 103 and 104. They are similar in general and have similar reference characters 5 on their similar parts. The reservoir unit is marked 301.

The compressor units have main cylinder walls 1, which have ports 2 for the admission of air at atmospheric pressure, and another series of 10 ports 3 and 80 for high pressure air. The latter ports are connected with manifolds 4 that feed into the reservoir unit 301.

The main cylinders of the compressor units are each provided with a valve sleeve 5 that has 15 ports 6 for low pressure and ports 60 for high pressure, while ports are provided in the head wall for back pressure relief. The valve sleeve moves or reciprocates in the main cylinder, closely fitting against the walls 1 and the ports are 20 provided in the forward end, the central portion and rear end portions as shown in the drawings, so that the functioning of the ports with respect to other cylinder ports may be in accordance 25 with the working operation decided for the compressing cylinder system in the embodiment. The valve sleeve is provided with a bracket 7 which is connected with a gear rack 8, operated by a gear 11 mounted on a shaft 9 that is operated 30 from a motor in a manner to be described.

Operating and moving within the valve sleeve are two so-called outer pistons, 10 and 20, which are arranged at the front and rear portions of the compressor, respectively, and holes 161 are 35 provided in the head of cylinder 10 for back pressure relief. These are compressing cylinders, and are connected together with rods 12, as indicated, which are slidable through a guiding spider 13, that guides them suitably. The spider 40 13 is an integral part of the valve sleeve 5. The outer pistons are provided with ports 14, for low pressure, which register with the low pressure ports 6 in the valve sleeve 5, at proper intervals. They are also provided with high pressure ports 45 140 which register with the high pressure ports 60 in the valve sleeve, at proper intervals. Both sets of ports 6 and 14 periodically register with ports 2 in the main cylinder wall. Likewise, high pressure ports 60 and 140 register with ports 3, 50 50 in the main cylinder wall 1, at proper pre-determined intervals.

The outer piston 10 is provided with a large valve opening 15 centrally located at one end. This opening is closed by a plate valve 16, mount- 55

ed on a hollow shaft 27, which is reciprocable, and also has another plate valve 18, which closes the central port 19, in outer piston 20.

The travel of the valves 16 and 18 is started by the movement of the valve sleeve 5, of which the spider 13 is an integral part and bears on one of the lugs 21, on hollow shaft 27, as it slides along the rods 12, thereby seating the valve 16 or 18 in the end of outer piston 10 or 20, respectively, as the stroke of the outer pistons, 10 and 20, inner pistons, 26 and 36, begins. The spider continues to bear on the lug 21 through a proportion of the stroke of the pistons, which is two-thirds, in this embodiment, and, as the pistons continue to the end of the stroke, the stress of compression retaining the valve 16 or 18 in its seat, the valve sleeve 5, and consequently, the spider 13 come to rest, but the other lug 21, on hollow shaft 27, reaches a bearing position on the spider 13, in preparation for the return stroke of the valve sleeve.

An inner piston 26 disposed at one end of the cylinder and inside of the outer piston 10 reciprocates within the latter. This inner piston is also connected with another inner piston 36, operating within the outer piston 20, by the piston rod 17 which also is guided and supported by 27 and 22 as indicated in the drawings. The piston rod 17 is operated by a rack 28, through gears 29. This gear travels on a rack 128, operated by rack 28 at predetermined periods.

The cylinder is supported on a base 30 which is arranged to also support the motor. The reservoir unit 301 is provided with valve 31, to control the air to and from the latter and service pipe 32.

The main shaft 50 operates a bevel pinion gear 59 which in turn operates the gears 67. The latter drive cam members 68 and cam rods 69 and segmental gears 70 on their supports 71 and drive gears 72 which operate shaft 9.

The operation of the recompressing system is as follows:

The motor is started up, at the same time the compressing cylinders are operated through the shaft 50, the gears 59 and 67, cam 68, rods 69, the segmental gears 70 and spur gears 72 and shaft 9 in sequence. When the shaft 9 rotates, it operates, for instance, the valve sleeve 5 of compressor unit 104, while at the same time, the respective shaft 9 pulls out the shafts 22 and 17 of compressor unit 103, causing the outer pistons 10 and 20, the inner pistons 26 and 36 to travel toward the front end. This action causes the atmospheric air to be drawn in through ports 2 in cylinder wall 1 of unit 103, thence through ports 6 in valve sleeve 5, thence through ports 14 into outer piston 10, because the ports have registered to permit it. The piston 26 in cylinder 10, by its movement toward the front end, produces a vacuum that draws in this air. It reaches the end of its stroke during this time, the valve 16 is closed, the ports 14 are closed, as well as ports 2 and 6. At the same moment ports 3, 60 and 140 in piston 10 are opened, while all the ports in piston 20 are closed but the valve 18 is open. The ports 80 and 81 are always in open registry. The next step that follows occurs, and the sleeve 5 starts its return travel, this causes the spider 13 to bear on the lug 21 moving the hollow shaft 27 and thereby causing the valves 16 and 18 attached to it to open and close respectively. The shafts 17 and 22 then begin their return stroke and move inner

pistons 26 and 36 and outer pistons 10 and 20 respectively. The ports 2, 6 and 14 of the outer piston section 20 come into registry, while all the ports at the opposite end or section where outer piston 10 is closed. The air under atmospheric pressure is then drawn into piston 20. At the same time, inner piston 26 commences to expel air from outer piston 10 through the opening 15 into the central chamber of the cylinder and through the ports 80 and 81 into manifold 4. Then pistons and sleeves continue traveling and eventually the ports 3, 60 and 140 of the piston section 20 come into alignment and communicate with the outlet 3.

All compressing cylinders are double acting and each of the so-called outer pistons 10 and 20 functions alternately as a piston and loading chamber in the movement of its "loading" stroke, and as a discharge chamber in the movement of its delivery stroke.

When two cylinder chambers are made into one chamber by the unseating of a valve between the two, the compression contained therein bears with equal stress on each end. If this compression is raised in pressure during the operation, the equality of stress is still maintained effective at each end of the chamber at all times, irrespective of to what pressure the air may be compressed.

If one end of the compressing chamber is an eight inch diameter piston, in a cylinder of eight and a half inch outside diameter and the other end of the chamber is, through the open end of the valve seat of the cylinder from which a valve has been unseated, the closed end of an eight and a half inch outside diameter cylinder (now operating as a piston) and joined to the first cylinder mentioned by means of connecting rods, then the equal bearing pressure of air in the chamber bears with appropriate force on the piston head of eight and a half inch diameter with valve seated, and on the piston end of lesser diameter.

This appropriate force bearing on the piston head of outer piston 10, for instance, with valve 16 seated, effective through hollow shaft 22, yoke 24, rack 23, and gear 123 is expressed at shaft 9 in the direction of compression, and the equal bearing force on piston 36 in cylinder 20 effective through piston rod 17, yoke 125, gear 29 (which it contacts centrifugally) rack 28 and gear 124 is expressed at the same shaft 9 and opposed to the direction of compression.

The ratio of gears 29 and 124 and the relativity of this ratio to gear 123 determines the status of the shaft 9 and may show a surplus of energy in the direction of compression in accord with these ratios, which surplus is opposed to compression and frictional resistances, while effecting economies in the consumption of drive power, see Figure 9.

Similarly the same condition prevails when the piston head of "loading" chamber 20, with valve 18 in its seat, and the appropriate bearing force thereon, recedes before the advance of compression piston 26, through discharge chamber 10, with valve 16 unseated.

The movement of the sleeve unseating the valve in the first compressor, effected from another compressor, and movements of the sleeves in four double acting compressors, accomplish, by similar movements in each compressor, a movement of the compressor next to follow, then throwing the entire series into the reverse action of these same double-acting compressors.

The operation of the compressing cylinders, 75

pistons and valves is timed to suit the work. The closure and opening of ports may be set to work to any predetermined sequence to suit the system, and will be self evident to those skilled in the art.

The motor 13 proceeds through its mechanical connections to rotate shaft 50 operating the cams 68 through the bevel gears 59 and 67. The cam rods 69, segmental gears 70 and drive gears 72 are then operating shafts 9 and their incidental compression valve controls. Following is the operation of compressor unit 101, which is typical of the others:—The shaft 9 of this unit, through its gear 11, rack gear 8, moves the valve sleeve 5 in the direction of the arrow shown in the diagram in Figure 8. This sleeve begins to close high pressure ports 3 and 60 in outer piston 10, at the same time it begins to open low pressure ports 2 and 6 in outer piston 20. The spider 13 incidentally contacting the lug 21 on hollow shaft 27 seats valve 18 in outer cylinder 20, converting it to a piston, and unseats valve 16 in outer piston 10, converting it to a discharge chamber. In order to move the outer pistons 10 and 20, which are next moved in this unit, connections through hollow shaft 22, connected to yoke 24, connected to rack 23 are propelled by a pinion 123 which is attached on one of the shafts 9 belonging to another of the compressor units, which in this case is 102. On the last mentioned shaft 9 are located gears 124 which operate the racks 28 moving the gears 29 placed on yoke 125. This yoke propels the inner pistons 26 and 36 through the rod 17.

The movement of the outer pistons in relation to the cylinder walls and the inner pistons changes the positions of the ports as indicated in the drawings.

Due to the position of the outer and inner pistons in this compressor unit, air is drawn through the low pressure ports 2, 6 and 14 into outer piston 20, while the air in the piston 10 is being expelled through the opening 15 by piston 26 into the central chamber, and thence out of pipe 80. A moment later, in the continuation of the stroke, the sleeve 5 moves its port openings so that the low pressure ports 2, 6 and 14 of outer piston 20 are cut off, and high pressure ports 3, 60 and 140 of the same piston are opened. This allows the expelled air from the central chamber to pass into the last mentioned high pressure ports. The return stroke now begins, and the sleeve and pistons approach the position shown in unit 103 of Figure 8. The atmospheric air is then drawn in through ports 2, 6 and 14 of outer piston 10 through forward travel of inner piston 26, while the air in piston 20 is expelled by piston 36 into the central chamber through the outlet 19.

The travel continues until the unit approaches the position of the ports indicated in 101 of Figure 8. In this view, the atmospheric ports 2, 6 and 14 of outer piston 10 are closed, and the high pressure ports 3, 60 and 140 are opened allowing the built-up-pressure air from the central chamber through manifold 4 inlet 3 to enter into chamber of outer piston 10.

It is, of course, noted that the operations of the various compressing cylinder units are not in unison so far as the sleeve and pistons are concerned, but according to the timing as indicated in general in Figure 8 which illustrates the sequence diagrammatically.

The system is progressively arranged for the increase of pressure in the compressing cylinders

and provides, by its arrangement, a balanced power, particularly on the valve plates 16 and 18, and central chamber and pistons 10 and 20. This permits an easy movement of the parts and prevents excessive frictional resistance as well as other disadvantages.

While but one form of this invention is indicated in the drawings, it is not intended to limit this application for patent to this particular system, except insofar as limited by the prior art, as it is appreciated that other forms might be developed and used that would use the same principles and come within the scope of the appended claims.

Having thus described the invention what is claimed is:—

1. In an air compressing machine, the combination of an air storage tank, a plurality of air compressors connected with the said storage tank, a plurality of driving shafts, relative to the said air compressors, a plurality of gears mounted on said shafts, said gears being meshed with respective geared racks joined to terminals of respective piston connecting rods that control, within the compressors, reciprocating movements of a plurality of outer pistons, joined together by rods, and a plurality of inner pistons, mechanically connected, reciprocating within the said outer pistons, when the said driving shafts are actuated by a motor reciprocally, through mechanical connections in sequence and cam travel control.

2. In an air compressing machine, the combination of an air storage tank, a plurality of air compressors connected with the said storage tank, a plurality of driving shafts, respective to the said air compressors, a plurality of gears mounted upon them, said gears being meshed with geared racks that control, from the terminals of respective piston connecting rods, reciprocating strokes of outer and inner pistons in the air compressors, by reciprocating rotations of the said driving shafts, and means for coordinating the said plurality of air compressors in a timing adjustment designed for the system, by extension of each of the said driving shafts, to the next compressor to operate, having a gear mounted thereon meshed with a geared rack adjoined to a valve sleeve in the last mentioned compressor, effecting, thereby, reciprocating movements of the said valve sleeve, in unison with the movements of the outer pistons in the first mentioned, or preceding, compressor.

3. In a system of the class described, a double-acting compressor, comprising the combination of an outer cylinder having ports in the wall thereof, a valve sleeve reciprocable in the said wall and having ports in the wall thereof to coincide with the first mentioned ports, and a spider rigidly affixed within its central portion for alternately seating and unseating central valves in the ends of interchangeable compressing chambers during the reciprocation, thereby converting the interchangeable compressing chambers to alternately operate as an outer piston and loading chamber, and as a discharge chamber, respectively.

4. In a double-acting compressor of the class described, a valve sleeve reciprocable within an outer cylinder, having a plurality of orifices in the wall thereof for the admission of air at normal and high pressures, adapted to coincide with a plurality of orifices in the said outer cylinder wall during its reciprocation, a large central port in the wall thereof, maintained in constant open

registry with a central port in the said outer cylinder during its reciprocation, to permit the constant passage of air at high pressure therefrom, and a spider rigidly affixed within the valve sleeve, adapted to move in unison therewith and effect reciprocating strokes of a plurality of central valves mounted upon a sleeve passing through the centre thereof.

5. In a system of the class described, a double-acting compressor, comprising, in combination, a sleeve, pistons and travel controls, and mechanism operated by the motor for effecting the reciprocal movements of the pistons, and of a valve sleeve, which, by a centrally located spider, therein, seats and unseats central valves, alternately, in the ends of interchangeable compressing chambers, converting the interchangeable compressing chambers to alternately operate, respectively, as outer piston, with a dynamic force of 10 compression bearing thereon, and as discharge chamber, with a statical force of compression bearing on an inner piston, therein through the open end of the discharge chamber from which the central valve has been unseated.

25. 6. In a double-acting compressor of the class described, in combination a quadruple piston arrangement, consisting of two outer pistons, or interchangeable compressing chambers, joined together by rods, having a plurality of ports in 30 the wall thereof, and reciprocating within a valve sleeve, and two inner pistons, mechanically connected, and reciprocating within the so-called outer pistons, in the ends of which are formed central ports, in which, and from which, are alternately seated, and unseated, central valves 35 mounted upon a hollow shaft passing through the centre of a spider rigidly affixed in, and reciprocating in unison with, the said valve sleeve.

7. A compressor of the class described, comprising the combination of an outer cylinder having ports in the wall thereof, a valve sleeve reciprocable in the said wall, and having ports in the wall thereof to coincide with the first mentioned ports, a plurality of outer pistons attached 40 together by rods, reciprocable in the sleeve, and having ports therein to periodically register with the ports in the outer cylinder, a plurality of inner pistons attached together mechanically and reciprocable in the outer pistons, and adapted 45 to draw air through the outer piston ports and compress it therein, means for operating the valve sleeve and pistons, and a support for the cylinder.

8. In a system of the class described, a compressor unit, comprising in combination, a cylinder wall having a plurality of orifices therein, for the admission of air at natural and high pressures, a plurality of outer pistons operating within the said cylinder, having ports therein to 50 correspond, during operation, with the orifices in said cylinder wall, and joined together by rods, a plurality of inner pistons, mechanically connected, operating within the said outer pistons, and having walls arranged to close off the ports of 55 said outer pistons during the operation, and central ports formed in the said outer pistons for opening and closing passages within the said outer pistons, and controlling the passage of com-

pressed air there-through, and means for operating the outer and inner pistons in the said cylinder.

9. In a system of the class described, a compressor unit, comprising in combination, a cylinder with walls provided with ports, a valve sleeve reciprocable in said cylinder and having ports to periodically align with the ports in the cylinder wall during its reciprocation, a plurality of outer pistons, joined together by rods, reciprocable in the said sleeve, and having ports to periodically coincide with those in the sleeve, a plurality of inner pistons, attached together mechanically, adapted to move in said outer pistons, a plurality of central valves, adapted to 10 operate periodically in unison with the motion of the sleeve, and open and close the passages of compressed air through the said outer pistons, and means for operating the said sleeve, central valves, and outer and inner pistons that cause 15 the respective forces of compressed air exerted on the outer and inner pistons to be exercised on a common shaft in opposition.

10. In a double-acting compressor of the class described, in combination a plurality of central valves, mounted upon a sleeve passing through the centre of a spider, and adapted to be alternately seated and unseated in central ports formed in the ends of interchangeable compressing chambers, or outer pistons, by reciprocating movements of the spider bearing on abutments upon the said sleeve, in coordination with a timing adjustment to suit the system.

11. In a system of the class described, a common shaft actuated by a motor reciprocally, through mechanical connections in sequence, and cam travel control, and, by gears fixed upon the common shaft, and meshed with geared racks, effecting the reciprocal strokes of outer and inner pistons in a compressor unit by the common shaft 35 so rotated, which is extended to another compressor unit, and, by a gear fixed upon it, and meshed with a geared rack adjoined to a valve sleeve in the last mentioned compressor unit, effecting a movement of the valve sleeve, its high 40 and low pressure intake port controls, and a centrally located spider, therein, incidentally seating and unseating central valves in so-called outer pistons.

12. In a compressor of the type described, a 50 centrally located spider rigidly affixed within a valve sleeve and adapted to bear, alternately, on abutments placed upon the sleeve of central valves passing through the centre thereof, effecting the reciprocal movement of the central valves 55 in coordination with a timing adjustment to suit the system, thereby opening and closing passages through outer pistons, and creating a balance of the dynamic and statical forces of compression within the compressor bearing, respectively, on the outer piston with centre valve seated, and on the inner piston, through the open end of the so-called outer piston from which the centre valve has been unseated, thereby making it possible to operate, from the motor, a series of such 60 compressor units, with opposing forces balanced in each unit.

HOWARD MORGAN.
